WALL ORNAMENT

William E. Crawford, 5428 Spring Road,
Bladensburg, Md.

Filed June 29, 1962, Ser. No. 70,736

Term of patent 14 years

(Cl. D29—23)

FIG. 1

FIG. 1 is a front elevation of the wall ornament, FIG. 2 is a top plan view of the wall ornament shown in FIG. 1, and

FIG. 3 is a side elevation thereof.

The back of the article is substantially plain and unornamented.

The essential features of the design reside in the full line portions on the drawing.

I claim:

The ornamental design for a wall ornament, substantially as shown and described.
